UNITED STATES PATENT OFFICE

132,428

DESIGN FOR A DEVICE FOR BREWING BEVERAGES

Clarence Karstadt, Glen Ellyn, Ill., assignor to Sears, Roebuck and Co., Chicago, Ill., a corporation of New York

Application October 20, 1941, Serial No. 103,829

Term of patent 7 years

To all whom it may concern:

Be it known that I, Clarence Karstadt, a citizen of the United States of America, residing at Glen Ellyn, in the county of Du Page and State of Illinois, have invented a new, original, and ornamental Design for a Device for Brewing Beverages, of which the following is a specification, reference being had to the accompanying drawing, forming a part thereof.

I claim:

The ornamental design for a device for brewing beverages, substantially as shown.

CLARENCE KARSTADT.
